CARPET.

No. 17,789.

Patented Oct. 11, 1887.

UNITED STATES PATENT OFFICE.

JOSEPH WISHART, OF NEW YORK, N. Y., ASSIGNOR TO THE BIGELOW CARPET COMPANY, OF CLINTON, MASSACHUSETTS.

DESIGN FOR A CARPET.

SPECIFICATION forming part of Design No. 17,789, dated October 11, 1887.

Application filed August 30, 1887. Serial No. 218,317. Term of patent 3½ years.

To all whom it may concern:

Be it known that I, JOSEPH WISHART, of New York city, in the county and State of New York, have invented a new and original 5 Design for Carpets, of which the following is a specification, reference being had to the accompanying photograph, which forms a part of the same.

The invention relates to a design to be 10 worked into or upon surfaces, such as carpets or similar fabrics; and it consists in the novel configuration and grouping of figures herein specifically shown and claimed.

The accompanying photograph is a face view 15 of a carpet showing my new design.

My design is for a carpet-border, and consists of an inner band having its edges curved so as to form an irregular wavy outline. This band is ornamented by a stem-work bearing 20 circular flowers and leaves. The middle portion of my border consists of double sprays

bearing leaves and flowers. The stem of the sprays is light and has two main branches extending in opposite directions. The flowers are generally circular in form, and a number 2 of small buds are supported at the ends of the stems. Underneath these sprays are inconspicuous flower forms larger in size, but appearing somewhat indistinct, like shadow-work. The outer margin of the border is plain in character, and is separated from the middle portion by a line of ornamental forms and small flower groups alternately arranged.

What I claim as new, and desire to secure by Letters Patent, is—

The design for a carpet-border, consisting of the design substantially as shown.

JOSEPH WISHART.
